AUTOMOBILE RADIATOR CLEANING DEVICE

Anthony E. Lavender, Hartford, Conn.

Application August 27, 1947, Serial No. 770,940

3 Claims. (Cl. 134—165)

1

This invention relates to a device for cleaning automobile radiators and similar devices by agitating the radiator in a tank of cleaning solution.

It is an object of this invention to provide an agitator of the kind to be more particularly described hereinafter for cleaning automobile radiators in which the radiator is supported in a tank of cleaning solution on a carriage which is slidably mounted in the tank, whereby the radiator is agitated for agitating the solution within the radiator so that the radiator may be thoroughly cleaned in a minimum length of time.

Another object of this invention is to provide an agitator of this kind which is so constructed and arranged that the radiator may be supported in a carriage on the inside of a fluid tank and means are provided for moving the carriage in reversing direction so the radiator may be effectively cleaned.

With the above and other objects in view, my invention consists in the arrangement, combination and details of construction disclosed in the drawings and specification, and as more particularly pointed out in the appended claims.

In the drawings,

Figure 1 is a longitudinal section, partly broken away, of an agitator constructed according to an embodiment of my invention.

Figure 2 is a top plan view, partly broken away and partly in section, of the carriage within the cleaning tank.

Figure 3 is a fragmentary horizontal section, partly broken away, showing the connection between the lever and the carriage.

Figure 4 is a fragmentary transverse section taken on the line 4—4 of Fig. 3.

Figure 5 is a fragmentary top plan view of the crankshaft and connections.

Referring to the drawings, the numeral 10 designates generally a tank for containing a cleaning fluid for cleaning the radiators of automobiles or the like. The tank 10 is provided with an agitator 11 for moving the radiator about within the tank, to provide for the thorough cleansing thereof. The normal methods of cleaning objects of this kind is to permit a cleaning fluid to soak in the channels and tubes of the radiator. The size of the objects is such as to preclude the ready agitating or shaking of the objects to permit a more thorough passage of the cleaning fluid throughout the tubes. With the use of a tank having an agitator of this kind, such large objects may readily be agitated while submerged in the cleaning fluid, to provide for a more thorough cleansing.

2

The tank 10 is formed of outer walls 10a which may be made of concrete or other suitable material. The walls 11 are lined with a metal lining 12. A pair of oppositely disposed guide members 14 are secured to the bottom wall 15 of the metal lining by welding 16, or other suitable fastening means.

The guides 14 are formed of L-shaped angle irons 17. A pair of inwardly opening guides 14 10 are fixed on the opposite sides of the tank 10. A carriage 18 is slidably mounted within the tank 10 on the rails or guide members 14. The carriage 18 is also made of channelled iron members 19 which form the outer members of the frame.

Intermediate frame members 20 are fixed between the opposite horizontal side members of the carriage 18 in longitudinally spaced apart relation along the length of the carriage. A pair of rollers 21 are rotatably mounted on the carriage 18 adjacent each end thereof. Each of the rollers 21 is engaged within one of the guide members 14.

A lever 22 is rockably mounted within the tank 10 on a bracket 24 which is fixed to one of the vertical side walls of the lining 12. The bracket 24 is formed of a pair of spaced apart arms 25 between which the lever 22 is engaged. The bight 26 of the bracket 24 is secured to the wall of the tank by welding 27 or other suitable fastening means.

A pin 28 engages through the arms 25 and through the lever 22 intermediate its length. The arms of the lever 22 on the opposite sides of the pivot 28 are disposed in inwardly divergent relation to each other so that the pivot of the lever may be disposed as close as possible to the side wall while permitting the maximum amount of free movement of the outer ends of the arms.

One side wall of the tank 10 is formed with a horizontal opening 29 therethrough. A bearing 40 or sealing member 30 is secured in the opening 29 at each end thereof. A shaft 31 is slidably disposed through the wall of the tank 10, engaging in the bearing 30. Each end of the shaft 31 is bifurcated to provide a pair of horizontal arms 45 32 at each end thereof. The arms 32 engage at one end of the shaft 31 on opposite sides of the lever 22 at its upper end.

A pin 34 engages between the arms 32 and is disposed within an elongated slot 35 formed in 50 the upper end of the lever 22. The pin 34 is free to slide in the slot 35 on rocking of the lever 22 effected by sliding movement of the shaft 31. A connecting rod 36 is pivotally connected between the arms 32 at the other end of the shaft 55 31 by a pivot pin 37.

A crankshaft 38 is rotatably supported between a pair of oppositely disposed inverted V-shaped brackets 39. The crankshaft 38 is formed with a single offset 40 with which the other end of the connecting rod 36 is engaged. A pulley 41 is fixed on one portion of the crankshaft 38 coaxially with the bearings therefor.

A belt 42 or other flexible driving member is trained about the pulley 41 and about a pulley 44 fixed on the drive shaft of a motor 45. The motor 45 and the crankshaft bearings 39 are fixed securely on the upper end of a supporting stand 46 disposed adjacent the tank 10. The lower end of the lever 22 is formed with an elongated slot 47. A pair of forwardly extending arms 48 are fixed on one end of the carriage 18 intermediate the width thereof.

A connecting pin 49 is fixed between the arms 48 and engages within the slot 47, whereby the carriage 18 may be rolled or slid along the length of the guide members 14 upon rocking of the lever 22 effected by rotation of the crankshaft 38.

In the use and operation of this cleaning device, the radiator or other large object is placed on the carriage 18 within the tank 10, which is filled with a suitable cleaning fluid. When power is applied to the motor 45, the carriage 18 and the object disposed thereon will be agitated within the tank 10 for effecting the thorough cleaning of the object.

I do not mean to confine myself to the exact details of construction herein disclosed, but claim all variations falling within the purview of the appended claims.

Having thus described my invention, what I claim is:

1. In an open fluid tank, an article supporting member including a rectangular frame having an upstanding flange formed on the marginal edges thereof, and a plurality of transverse supporting members having the opposite ends thereof secured to the side members of said frame, transverse axle members carried below said frame, rollers rotatably mounted on the opposite ends of said axles, guide means on the bottom of said tank and engaging said rollers, a lever rockably mounted intermediate the length thereof, on an end wall of said tank, means connecting one end of said lever and said frame, a shaft slidably extending through said end wall and having one end connected to the other end of said lever, and means connected to the other end of said shaft for reciprocating said shaft whereby an article positioned on said article supporting member will be reciprocated in said open fluid tank.

2. In combination, an open fluid tank, an article supporting member in said tank including a rectangular frame, and a plurality of transverse bars fixed thereto, transverse axle members carried below said frame, rollers rotatably mounted on the opposite ends of said axles, angle members secured to the bottom of said tank and having upstanding flanges disposed outwardly of said rollers to provide guide means for said frame, a lever rockably mounted intermediate the length thereof on an end wall of said tank, means connecting one end of said lever and said frame, a shaft slidably extending through said end wall and having one end thereof connected to the other end of said lever, and reciprocating means connected to the outer end of said shaft whereby an article positioned on said article supporting member will be reciprocated in said open fluid tank.
3. In combination, an open fluid tank, an article supporting member in said tank including a rectangular frame, transverse axles carried below said frame, rollers rotatably mounted on the opposite ends of said axles, guide means on the bottom of said tank including upstanding flanges on opposite sides of said rollers, a lever rockably mounted intermediate the length thereof on an end wall of said tank, longitudinal slots formed in said lever adjacent the respective ends thereof, a pin carried by one end of said frame and slidably engaging in one of said slots, a shaft slidably extending through an end wall of said tank, means on the inner end of said shaft slidably engaging in the other of said slots, and means connected to the outer end of said shaft, and adapted to cause reciprocation thereof whereby an article positioned on said article supporting member will be reciprocated in said open fluid tank.

ANTHONY E. LAVENDER.
